UNIVERSAL WRENCH

Tony L. Hobbs, 6808 Velda Court,
Bakersfield, Calif. 93306

Filed Nov. 14, 1966, Ser. No. 4,661

Term of patent 14 years

(Cl. D54—16)

FIG. 1 is an elevational view of one side of my new universal wrench design;

FIG. 2 is a top plan view of my wrench design;

FIG. 3 is an elevational view of the other side of my new design;

FIG. 4 is a view of one end of the new wrench design; and,

FIG. 5 is a view of the other end of my new design.

I claim:

The ornamental design for a universal wrench, as shown and described.
